UNITED STATES PATENT OFFICE.

KNULAND H. SHAFFER, OF HUDSON, NEW YORK.

DESIGN FOR A BADGE.

SPECIFICATION forming part of Design No. 29,276, dated August 30, 1898.

Application filed August 3, 1898. Serial No. 687,657. Term of patent 3½ years.

To all whom it may concern:

Be it known that I, KNULAND H. SHAFFER, of Hudson, New York, have invented a certain new and useful Design for a Badge, of which the following is a specification.

My invention relates to a design for badges; and it consists in the configuration and shape, as shown in the drawing, which will be more fully described hereinafter.

- 10 A represents the plate or shield, which depends from a support, as B, by two short chains b. The plate or shield A is surmounted by the representation of an eagle a⁶, to the spread wings of which are secured the ends 15 or the suspending-chains b. The shield is annular in shape, the upper face thereof being partially plain and containing at its extreme upper end a rectangular-shaped space a', the end of the said rectangular forming the 20 junction between the parts representing the eagle and the shield. The plain surface of the shield and rectangular space is adapted to receive suitable matter, as print or design or legend, that may be placed thereon. The 25 said upper outer edge of the plain surface of the shield contains a marginal border-line.

Upon the lower outer surface of the shield is a border in scroll, representing laurel-wreath a⁵, divided by a panel a, with a plain surface adapted to receive suitable matter, as figures or legend. The center of the shield A is a panel or shield a⁴, comprising a representation of a portion of the American and Cuban flags. Across the center thereof is a diagonally-arranged superimposed panel a², with 35 plain surface adapted to receive suitable inscription or design or legend. While my badge is shown of a size suitable for attachment to wearing-apparel, yet I do not wish to be understood as confining myself to this particular size, as the device may be made much larger and suitable for other analogous purposes.

Having thus described my invention, I claim—

The design for a badge substantially as shown and described.

KNULAND H. SHAFFER.
